COMBINATION FURNACE AND WATER HEATER

Arthur Doherty, Los Angeles, Calif.

Application June 17, 1940, Serial No. 340,865

10 Claims. (Cl. 126—101)

This invention relates to heating, ventilating, and water heating apparatus, and has for an object the provision of an improvement in the construction of this general type of apparatus whereby it is made commercially feasible to provide a hot air furnace and water heater combined in a single, unitary structure.

Another object of my invention is the provision of a combined furnace and water heater, wherein both the furnace element and the water heater element are capable of operating entirely independently of each other when occasion demands and yet wherein, under normal circumstances of use, a certain inter-co-operation exists between the two elements whereby the total cost of heating the atmosphere and supplying hot water is reduced.

A more detailed object in this connection is the provision of a combined hot air furnace and water heater, both enclosed in a single, unitary housing and so disposed therein with respect to each other that a large portion of the heat from the furnace which otherwise would be dissipated through the walls of the furnace and lost, is saved and utilized to aid in keeping the water within the water heater at the desired temperature, and thus effecting a decrease in the amount of fuel which must be supplied to the water heater burner. In other words, the device of the present invention decreases the cost of heating the atmosphere of, and supplying hot water to a home or the like, by reducing the "stand by heat loss" of the water heater to a minimum.

A further object is to provide a combined furnace and water heater, as described, wherein in each of the two heating devices is of ample capacity to meet the requirements apt to be imposed upon it to serve the needs of the house, apartment, or other place of its installation.

A further object of my invention is to reduce not only the cost of operating both a furnace and water heater, but the cost of purchase and installation, as well, the installation costs being reduced to a minimum by the apparatus of my invention for the reason that both the furnace unit and the water heater unit utilize a common vent or flue for the dissipation of waste products of combustion, and both also utilize a common fuel supply. Economy of space required for installation of the furnace and water heater is also an advantage gained by the apparatus of the present invention, which, in certain types of installation, bears an importance even greater than that which attaches to cost of in-

stallation and operation, for the reason that by virtue of the fact that both the furnace and the water heater are assembled within a single, unitary housing, both of these substantially essential household accessories can be installed in a space not materially greater than that heretofore required for a water heater alone.

Referring to the drawings:

Figure 1 is a view in front elevation of heating apparatus embodying the principles of the present invention.

Figure 2 is a longitudinal, medial, vertical, sectional view, the plane of section being taken on the line 2—2 of Figure 1 with the direction of view as indicated.

Figure 3 is a horizontal sectional view, the plane of section being indicated by the line 3—3 of Figure 2 and the direction of view by the arrows.

Figure 4 is a horizontal sectional view, the plane of section being indicated by the line 4—4 of Figure 2 and the direction of view by the arrows.

Figure 5 is a detail view partly in side elevation and partly broken away and shown in section to show the manner in which the apparatus is vented.

Figure 6 is a detail view in perspective of a portion of the corrugated radiating shell.

Figure 7 is an enlarged detail view in perspective of a portion of the radiating shell, the direction of view being indicated by the arrow 7 of Figure 6.

Figure 8 is a view in side elevation of one end of the male forming die used in the manufacture of the radiating shell of Figures 6 and 7.

Figure 9 is an end elevation, the direction of view being indicated by the arrow 9 of Figure 8.

Figure 10 is a top plan view of the female forming die.

Figure 11 is a transverse sectional view taken on the line 11—11 of Figure 10, and showing one of the corrugations of the radiating shell therein in the shape to which it has been formed by the male die of Fig. 9.

Figure 12 is a view similar to Figure 11, but taken on the line 12—12 of Figure 10.

Specifically describing that embodiment of my invention which has been chosen for illustration, my combination furnace and water heater is encased in a suitable housing 16 preferably square in plan. Within this housing inner and outer casings 17 and 18, respectively, are mounted, these casings preferably being cylindrical and disposed coaxially with the cas-

ing 17 telescoped within the casing 18. The inner casing 17 is of sufficiently less diameter than the outer to leave a passageway 19 of annular cross-sectional form therebetween; and this passageway 19 is divided into a large number of vertically extending ducts 21 by means of a radiating shell 22 of cylindrical form and having longitudinally extending corrugations 23 therein corresponding in height to the difference between the inside radius of the outer casing 18 and the outside radius of the inner casing 17. 5

Each alternate duct 21 is closed at its upper end 24, whereas the intervening ducts 21 are closed at their lower ends 26 with the result that all communication between the outside ducts 21 and the inside ducts is prevented. 10

The inside ducts 21 communicate at their lower ends with a firebox 27 within which a suitable source of heat such as a gas burner 28 is disposed; and at their upper ends these same 20 inside ducts communicate with a manifold space 29 defined by spaced horizontal plates 31 and 42. At one side, preferably the front of the heater, the manifold space 29 communicates as by a short horizontal passageway 33 (see Figures 1 25 and 5) with a flue pipe 34 adapted to be connected to a suitable chimney whereby to dispose of the waste products of combustion. As best shown in Figure 2, the upper plate 31 is above the plane of the closed upper ends of the inner 30 ducts 21 whereas the lower plate 32 is below the plane of those closed ends, with the result that all of the inner ducts open into the manifold space 29. Similarly, the top 36 of the firebox 27 is disposed in the plane of the lower end of 35 the inner casing 17 and above the plane of the closed lower ends of the inside ducts, with the result that products of combustion can pass freely from the firebox 27 into the vertically rising inside ducts. Inasmuch as the plate 36 defining the top of the firebox is exposed directly to the flame of the burner 28, it preferably is composed of suitable material to withstand the 40 severe temperatures it is apt to encounter. I have found that stainless steel is a very desirable 45 material of which to form this baffle plate 36.

The outer casing 18 is materially longer than the inner 17, extending at each end beyond the corresponding end of the inner. In fact, the lower end 37 of the outer casing 18 is sufficiently 50 longer to extend downwards beyond the firebox 27 far enough to accommodate a blow fan 38 driven by a motor 39 carried by suitable brackets 41 attached to cross braces 42. Preferably the lower end 31 of the outer casing 18 rests upon these same braces 42, there being a suitable extension 43 of the housing 16 below the cross braces 42 to accommodate the motor 39 and its brackets 41. The fan 38 preferably is of the centrifugal type and is adapted to draw air into the housing 16 through an opening 44 in the bottom of the housing 16 and to be forced upwards and outwards from the fan 38 so as to facilitate passage of the air around the outside walls of the firebox 27. Upon reaching the proximity of the upper ends of the firebox 27 the air enters the outside ducts 21 where it is separated from the heated products of combustion in the inside ducts, only by the thickness of the radiating shell 22; because of the very extensive area of this radiating shell attained by the large number of corrugations 23 formed therein, a very high efficiency of heat conduction is attained. From this series of outside ducts 21, the air thus heated 70 passes to a manifold collecting space 46 or 75

"plenum" as it is called in the trade, which is defined by the horizontal plate 31 as a bottom member and the top 41 of the housing 16 as its upper member. With this plenum, any desired number of hot air furnace pipes 48 communicate to conduct the heated air to whatever localities may be desired. 5

From the above description of the furnace portion of my improved apparatus it becomes apparent that the portion thereof wherein transfer of heat from the products of combustion to the ventilating air occurs comprises a pair of substantially cylindrical casings disposed one inside the other and having the corrugated radiating shell 22 disposed there between. This construction leaves a relatively large cylindrical space 51 inside the inner casing 17; and it is within this space that the water heater portion 52 of my invention is installed so as to take advantage of heat which otherwise would be wasted from the furnace portion of the device to at least aid in keeping the temperature of the water at the desired degree. The fact of the matter is that this object can easily be obtained, so hot does the compartment 51 tend to remain during normal operation of the furnace, that I find it expedient to line the compartment 51 with relatively heavy insulation 53 and 54 at the top and sides, respectively, of the compartment, and even heavier insulation 56 at the bottom, i. e., upon the upper surface of the baffle 36 which constitutes the top of the firebox 27.

The water heater portion 52 comprises a suitable cylindrical boiler 57 supported by brackets 58 and having a second burner 59 disposed therebelow. The boiler 57 is provided with supply and outlet pipes 61 and 62 respectively, the former preferably extending to a position 63 adjacent the bottom 64 of the boiler 57 in accordance with conventional practice so as to deliver the coldest water within the boiler to the point of maximum heat concentration. Adjacent the point 63 of discharge of the cold water into the boiler 57 a thermostat 66 is provided, this thermostat 66 extending through a wall of the boiler 57 and through both inner and outer casings to communicate with an automatic valve 67 adapted to supply fuel to the water heater burner 59 when the temperature of the water surrounding the thermostat 66 falls below a predetermined minimum. The valve 67 also supplies a pilot tube 68 and preferably is governed by a safety, thermally responsive element 69 adapted to prevent flow of gas through the valve 67 to the burner 59 except when the safety element 69 is heated. Similarly, the furnace burner 28 is adapted to be supplied with fuel through piping 71 leading from a valve 72 adapted to be controlled by a solenoid 73. Energizing of the solenoid 73 is effected by wires 74 leading from a relay control 76; and the furnace burner 28 also is provided with an automatic safety element 77, the sensitive end of which is disposed in position to be heated by the flame from the pilot tube 68 with the result that if the pilot light is extinguished the safety element 77 operates to prevent opening of the valve 72 which controls flow of fuel to the main furnace burner 28. Various co-operative features between the two portions of my apparatus exist, i. e., between the furnace portion and the water heater portion. They both receive fuel from a single supply pipe 81 which leads preferably through a pressure regulating valve 82 to a T-fitting 83 from which one line 84 leads through a manually operable valve 86

to the valve 72 of the furnace burner 28. The other line 87 from the T-fitting 83 leads through a manually operable valve 88 to the valve 67 of the water heater burner 59. Another feature in common is that both burners discharge to the same vent 34 inasmuch as from adjacent the top of the space 51 within which the water heater 52 is mounted preferably a plurality of horizontal passageways 91 lead to the same chamber 92 as that into which the passageway 33 leads. In order to prevent chance downdrafts in the vent 34 from blowing the flame off either of the burners 59 or 28 I prefer that the chamber 92 be provided with one or more openings 93 communicating with the bottom of the chamber below the passages 33 and 91 and that a deflecting shield 94 be positioned above the passages 33 and 91. Such an opening 93 may be provided on each side face of the chamber 92, in which event I prefer to provide plates 96 sloping upwards toward the center of the heater from below the two openings 93 to converge as at 97 below the passages 33 and 91.

One of the constructional details of my apparatus relates to the manner in which the corrugated radiating shell 22 is formed. Inasmuch as the inner and outer ducts are to be cut off from inter-communication, it is essential that each end of the shell makes contact throughout its entire periphery; and of course it is easier to establish and maintain such leak-proof contacts if the surfaces of the shell where they occur are smooth, i. e., devoid of irregularities such as the corrugations 23 formed in the other portions of the shell.

Maintaining a smooth surface of contact at the lower end of the shell 22 is relatively simple, inasmuch as the lower end extends past the top of the firebox 27 into embracing relationship with the walls thereof, with the result that the desired smooth surface of contact can easily be provided on the inner circular face of the shell simply by forming the ends 101 of the corrugations 23 so that they flatten out as they approach the end of the shell 22. No attention need be given to whether or not the end of the shell remains a straight line, for the reason that the actual end 102 is not called upon to establish any contact, but only the inner face 103 adjacent the end 102.

Formation of the upper end 107, on the other hand, presents a more difficult problem, inasmuch as the constructional requirements of the upper end of the manifold space 29 and the bottom of the plenum 46 are simplified if the single flat, relatively thin plate 31 be employed to provide this detail. Hence in order to present the straight line contact (or, more accurately, the smooth circular contact) with the plate 31 which is most practical, not only should the inner face 106 of the shell adjacent to the actual end 107 be smooth, but the end 107 also should be straight, or describe a circle lying substantially within a flat plane.

I have developed a design for a set of dies to accomplish this step of forming the upper end of the shell in a positive and efficient manner, a set of such dies being illustrated in Figures 8 to 12 inclusive. The female die 111 is preferably flat on its upper surface 112 and has a groove or channel 113 formed therein, substantially corresponding in height to the desired length of the corrugation 23 to be formed. In cross-sectional configuration, however, the channel 113 need not correspond to that of the de-

sired corrugation 23, for the reason that the only contact between the plate 114 being formed and the female die 111 (except at the ends of the corrugation) is on the upper surface 112 of the die. The corrugation 23 is formed simply by bending the plate 114 around the projecting entrant rib 116 of the male die 117, which is complementary in shape to the desired inner surface of the corrugation 23. At its ends, however, the channel 113 tapers down, as at 118, to a thin portion 119 the thickness of which is only a little greater than twice the thickness of the metal 114. The end 121 of the projecting rib 116 on the male die 117 is shaped substantially complementary to the tapered end 118 of the female die, except that it is not provided with a tongue adapted to enter the thin slot portion 119. When the male die enters the channel 113 of the female die pressing the metal of the plate 114 downwards thereinto, the portion of the plate which extends beyond the end of the rib 116 and therefore overlies the slot 119 of the female die is simply folded double and, because of the inherent stiffness which the metal possesses, forced downwards into the slot 119 substantially as illustrated in Figure 12.

Attention is invited to the fact that the rib 116 is of gradually decreasing height throughout the tapered portion 121 thereof, the purpose of 30 this construction being to permit the folding of the metal double as just described and as indicated at 126 without necessitating any stretching of the metal. The desirability for this feature is explained by the fact that throughout 35 the body of the corrugation 23 the corners are rounded, whereas at the doubled end 126 there are no round corners but the angles are all substantially 90 degrees. Therefore if the doubled portion 126 corresponded in height to the height 40 of the body of the corrugation 23 there would have to be an actual stretching of the metal but by permitting the projection 116 to decrease in height throughout the tapered portion 121 thereof 45 this actual doubling with contact between the two folds of the doubled portion can occur without any stretching.

The resultant construction is illustrated in Figure 7 which shows the straight edge 127 defining the actual end 107 of the shell 22 and two of the 50 corrugations 23 thereof with the ends 126 doubled and folded together so as to close the upper ends of the hollow interior portions of the corrugations 23 and still leave the edge 127 a perfectly straight line to which the plate 31 can be welded with the utmost facility.

I claim:

1. In a combination furnace and water heater, a unitary housing, coaxially disposed inner and outer casings mounted within said housing and spaced apart to define a passageway therebetween, a radiating shell disposed within said passageway and defining an inside and an outside duct separated only by said shell, a firebox disposed below said inner casing and communicating with said inside duct, means providing a flue communicating with the upper end of said inside duct, means providing an air inlet to said housing below said firebox, said outer casing extending downwards past said firebox to guide air moving upwards from said inlet into said outside duct, means adjacent the top of said housing providing a plenum into which said outside duct leads, a boiler mounted within said inner casing above said firebox, and supply and outlet pipes 60 communicating with said boiler.

2. In a combination furnace and water heater, a unitary housing, coaxially disposed inner and outer casings mounted within said housing and spaced apart to define a passageway therebetween, a radiating shell disposed within said passageway and having vertically extending corrugations defining an inside and an outside series of ducts separated only by said shell, a firebox disposed below said inner casing and communicating with said inside ducts, means providing a flue communicating with the upper ends of said inside ducts, means providing an air inlet to said housing below said firebox, said outer casing extending downwards past said firebox to guide air moving upwards from said inlet into said outside ducts, means adjacent the top of said housing providing a plenum into which said outside ducts lead, a boiler mounted within the space enclosed by said inner casing and the top of said firebox, and supply and outlet pipes communicating with said boiler.
3. In a combination furnace and water heater, a unitary housing, coaxially disposed inner and outer casings mounted within said housing and spaced apart to define a passageway therebetween, a radiating shell disposed within said passageway and having vertically extending corrugations defining an inside and an outside series of ducts separated only by said shell, a firebox disposed below said inner casing and communicating with said inside ducts, means providing a flue communicating with the upper ends of said inside ducts, means providing an air inlet to said housing below said firebox, said outer casing extending downwards past said firebox to guide air moving upwards from said inlet into said outside ducts, means adjacent the top of said housing providing a plenum into which said outside ducts lead, a boiler mounted within the space enclosed by said inner casing and the top of said firebox, supply and outlet pipes communicating with said boiler and insulation of predetermined athermous value lining said enclosed space to shield said boiler from excessive heat.
4. In a combination furnace and water heater, a unitary housing, coaxially disposed inner and outer casings mounted within said housing and spaced apart to define a passageway therebetween, a radiating shell disposed within said passageway and having vertically extending corrugations defining an inside and an outside series of ducts separated only by said shell, a firebox disposed below said inner casing and communicating with said inside ducts, means providing a flue communicating with the upper ends of said inside ducts, means providing an air inlet to said housing below said firebox, said outer casing extending downwards past said firebox to guide air moving upwards from said inlet into said outside ducts, means adjacent the top of said housing providing a plenum into which said outside ducts lead, a boiler mounted within the space enclosed by said inner casing and the top of said firebox, supply and outlet pipes communicating with said boiler, insulation of predetermined athermous value lining said enclosed space to shield said boiler from excessive heat, independently operating burners disposed within said firebox and below said boiler within said enclosed space, a fuel supply pipe, and means connecting both of said burners to said supply pipe.
5. In a combination furnace and water heater, a unitary housing, coaxially disposed inner and outer casings mounted within said housing and spaced apart to define a passageway therebetween, a radiating shell disposed within said passageway and having vertically extending corrugations defining an inside and an outside series of ducts separated only by said shell, a firebox disposed below said inner casing and communicating with said inside ducts, means providing a flue communicating with the upper ends of said inside ducts, means adjacent the top of said housing providing a plenum into which said outside ducts lead, a boiler mounted within the space enclosed by said inner casing and the top of said firebox, supply and outlet pipes communicating with said boiler, insulation of predetermined athermous value lining said enclosed space to shield said boiler from excessive heat, independently operating burners disposed within said firebox and below said boiler within said enclosed space, a fuel supply pipe, means connecting both of said burners to said supply pipe, a thermostatic means adjacent the top of said housing providing a plenum into which said outside ducts lead, a boiler mounted within the space enclosed by said inner casing and the top of said firebox, supply and outlet pipes communicating with said boiler, insulation of predetermined athermous value lining said enclosed space to shield said boiler from excessive heat, independently operating burners disposed within said firebox and below said boiler within said enclosed space, a fuel supply pipe, means connecting both of said burners to said supply pipe, a thermostat within said boiler, and a valve within the connecting means of said boiler's burner and operably coupled to said thermostat to be opened thereby when the supply of heat reaching said enclosed space is diminished to the extent that the temperature of water within said boiler falls below a predetermined degree.
6. In a combination furnace and water heater, a unitary housing, a firebox mounted in the lower portion of said housing, a shell embracing at its lower end the upper end of said firebox and having vertical corrugations defining inside and outside ducts, inner and outer casings contacting the inner and outer crests, respectively, of said corrugations, said inner casing terminating short of the lower ends of said corrugations whereby said inside ducts are left open to said firebox, a baffle plate defining the top of said firebox and extending across the lower end of said inner casing to direct products of combustion from said firebox into said inside ducts, means providing a flue communicating with the upper ends of said inside ducts, the lower end of said outer casing extending downward past said firebox in spaced relation therewith and having an air inlet therein, means providing a plenum at the top of said housing into which the upper ends of said outside ducts lead, a boiler disposed within said inner casing above said baffle, and supply and outlet pipes communicating with said boiler.
7. In a combination furnace and water heater, a unitary housing, a firebox mounted in the lower portion of said housing, a shell embracing at its lower end the upper end of said firebox and having vertical corrugations defining inside and outside ducts, inner and outer casings contacting the inner and outer crests, respectively, of said corrugations, said inner casing terminating short of the lower ends of said corrugations whereby said inside ducts are left open to said firebox, a baffle plate defining the top of said firebox and extending across the lower end of said inner casing to direct products of combustion from said firebox into said inside ducts, means providing a flue communicating with the upper ends of said inside ducts, the lower end of said outer casing extending downward past said firebox in spaced relation therewith and having an air inlet therein, means providing a plenum at the top of said housing into which the upper ends of said outside ducts lead, a boiler disposed

within said inner casing above said baffle, supply and outlet pipes communicating with said boiler, and insulation of predetermined athermanous value lining said baffle plate and said inner casing to shield said boiler from excessive heat from said firebox.

8. In a combination furnace and water heater, a unitary housing, a firebox mounted in the lower portion of said housing, a shell embracing at its lower end the upper end of said firebox and having vertical corrugations defining inside and outside ducts, inner and outer casings contacting the inner and outer crests, respectively, of said corrugations, said inner casing terminating short of the lower ends of said corrugations whereby said inside ducts are left open to said firebox, a baffle plate defining the top of said firebox and extending across the lower end of said inner casing to direct products of combustion from said firebox into said inside ducts, means providing a flue communicating with the upper ends of said inside ducts, the lower end of said outer casing extending downward past said firebox in spaced relation therewith and having an air inlet therein, means providing a plenum at the top of said housing into which the upper ends of said outside ducts lead, a boiler disposed within said inner casing above said baffle, supply and outlet pipes communicating with said boiler, a baffle closing the upper end of said inner casing above said boiler, a duct leading from inside said inner casing to said flue, and independently operating burners mounted within said firebox and within said inner casing below said boiler.

9. In a combination furnace and water heater a unitary housing, a firebox mounted in the lower portion of said housing, a shell embracing at its lower end the upper end of said firebox and having vertical corrugations defining inside and outside ducts, inner and outer casings contacting the inner and outer crests, respectively, of said corrugations, said inner casing terminating short of the lower ends of said corrugations whereby said inside ducts are left open to said firebox, a baffle plate defining the top of said firebox and extending across the lower end of said inner casing to direct products of combustion from said firebox into said inside ducts, means providing a flue communicating with the upper ends of said inside ducts, the lower end of said outer casing extending downward past said fire-

box in spaced relation therewith and having an air inlet therein, means providing a plenum at the top of said housing into which the upper ends of said outside ducts lead, a boiler disposed within said inner casing above said baffle, supply and outlet pipes communicating with said boiler, a baffle closing the upper end of said inner casing above said boiler, a duct leading from inside said inner casing to said flue, and independently operating burners mounted within said firebox and within said inner casing below said boiler, a fuel supply pipe, and a pipe connecting both of said burners to said supply pipe.

10. In a combination furnace and water heater, a unitary housing, a firebox mounted in the lower portion of said housing, a shell embracing at its lower end the upper end of said firebox and having vertical corrugations defining inside and outside ducts, inner and outer casings contacting the inner and outer crests, respectively, of said corrugations, said inner casing terminating short of the lower ends of said corrugations whereby said inside ducts are left open to said firebox, a baffle plate defining the top of said firebox and extending across the lower end of said inner casing to direct products of combustion from said firebox into said inside ducts, means providing a flue communicating with the upper ends of said inside ducts, the lower end 30 of said outer casing extending downward past said firebox in spaced relation therewith and having an air inlet therein, means providing a plenum at the top of said housing into which the upper ends of said outside ducts lead, a boiler disposed within said inner casing above said baffle, supply and outlet pipes communicating with said boiler, a baffle closing the upper end of said inner casing above said boiler, a duct leading from inside said inner casing to 40 said flue, and independently operating burners mounted within said firebox and within said inner casing below said boiler, a fuel supply pipe, and a pipe connecting both of said burners to said supply pipe, a thermostat within said boiler, 45 a valve within said connecting pipe of said boiler's burner and operably coupled to said thermostat to be opened thereby when the supply of heat reaching said boiler is diminished to the extent that the temperature of said boiler's contents falls below a predetermined degree.

ARTHUR DOHERTY
